DESIGN FOR A CHAIR

Alice L. Roth, Troy, Ohio, assignor to The Troy Sunshade Company, Troy, Ohio, a corporation of Ohio

Application January 22, 1940, Serial No. 89,628

Term of patent 7 years

To all whom it may concern:

Be it known that I, Alice L. Roth, a citizen of the United States of America, residing at Troy, in the county of Miami, State of Ohio, have invented a new, original, and ornamental Design for Chairs, of which the following is a specification, reference being had to the accompanying drawing forming a part thereof.

In the drawing:

Fig. 1 is a perspective view of the chair showing my new design;

Fig. 2 is a central vertical section through the seat and back of the chair; and

Fig. 3 is a horizontal section taken on line 3—3 of Fig. 1 about midway along the back of the chair.

I claim:

The ornamental design for a chair, substantially as shown.

ALICE L. ROTH.
